(57) **CLAIM**

The ornamental design for a display screen with animated graphical user interface, as shown and described.

DESCRIPTION

FIG. 1 is a front view of a display screen with animated graphical user interface with a first image in an animated sequence;

FIG. 2 is a front view of the display screen with animated graphical user interface with a second image in the animated sequence;

FIG. 3 is a front view of the display screen with animated graphical user interface with a third image in the animated sequence;

FIG. 4 is a front view of the display screen with animated graphical user interface with a fourth image in the animated sequence; and,

FIG. 5 is a front view of the display screen with animated graphical user interface with a fifth image in the animated sequence.

In the drawings, the outermost broken lines in the figures show a display screen or portion thereof and form no part of the claimed design. The appearance of the animated graphical user interface transitions between the images shown in FIGS. 1-5. The process or period in which one image transitions to another image forms no part of the claimed design.
